UNITED STATES PATENT OFFICE.

ITALO VIRONDA, OF BATTLE CREEK, MICHIGAN.

TAPPET FOR INTERNAL-COMBUSTION ENGINES.

Application filed October 5, 1927. Serial No. 224,135.

In internal combustion engines controlled by means of reciprocating valves, the valves and their connective tappets, necessarily should be machined to precision in order to 5 have proper co-operation between the valve and its seat, and the cam and its tappet, and when installed, owing to variation caused by contraction and expansion of the connective parts, carbon about the valve and 10 its seat, wear on both the tappet and its cam, nonconformity of action is produced, which not only affects the smooth and rhythmic operation of the motor and causes a loss of power and waste of fuel for the 15 engine, but also causes unnecessary wear of the operative parts and vexatious noise and clatter.

My invention contemplates a better, smoother, and more silent operation of the 20 valve in its seat and the tappet in connection with its cam for actuating its elevating movement, besides which it has advantages for adjusting the tappet with respect to its push-rod or valve stem whereby wear may be 25 readily compensated within reasonable latitude of the life of the structure and whereby noise may be reduced in the operation of the parts to a minimum, and whereby an engine equipped with tappets of like nature will run 30 more smoothly and freely, than could be the case where tappets of the usual rigid one piece construction are used.

The objects and advantages of my improved tappet construction will be more 35 fully set forth in the description following, taken in connection with the accompanying drawings forming a part of the specifications, in which:—

Fig. 1 is a longitudinal elevation with a 40 part of the tappet head broken away showing the connection with its push-rod, and

Fig. 2 is a perspective view of the adjusting thimble for attachment with the push rod.

As my invention is more particularly confined to a tappet and its operating push-rod, I have shown said tappet and a portion of 45 its actuating rod, only—it being understood that said tappet and its rod are actuated and 50 occupy the usual position in an internal combustion engine as are tappets generally in use.

As shown the tappet A, has a reduced internally screw-threaded stem 1, terminating 55 with a wrench hold 2, whereby said tappet may be held or turned in its connection with

an externally threaded shank 3, of a take-up or spacing member B.

It would be obvious however, that in lieu of the wrench hold 2, as shown, any other 60 position on the stem 1, of the tappet head below its operative position in its bearing on an engine would do for the purpose.

The take-up or spacing member B, at one end is enlarged and screw-threaded as designated by the character 4, and between its threaded extremities is formed with a blank space 5, in a form for being readily gripped with a wrench for purposes of adjustment with relation to co-acting parts. Surrounding the shank 3, and adapted to abut the barrel extremity of the tappet, a jam-nut 6, is screw-threaded on said shank for the purpose of preventing loosening of the parts 1 and 3, after adjustment. Extending from the 75 upper end of a push-rod C, and interiorly screw-threaded on the enlarged end of the take-up or spacing member B, a thimble 7 is fitted. This thimble is bored to nicely slide onto the upper portion of the push-rod 80 C, at which point said push-rod abuts the enlarged end of the spacing member as shown. The thimble, aforesaid, extends somewhat below a head 8 formed on the end of said push-rod and an annular groove 9, 85 separating said head from the bottom of said thimble, the groove being for the purpose of receiving a split ring 10.

The push-rod of necessity is somewhat of smaller diameter than the interior of the 90 thimble for the purpose of receiving the retaining split ring 10, which lies on the bottom of said thimble and forms a shoulder for preventing the removal of said push-rod when in operative position. The ring 10, is 95 introduced into the groove 9 when the push-rod groove has been raised above the free end of the thimble 7, and said ring is machined to nicely fit within the chambered wall of said thimble and the groove of said 100 push-rod when the parts are assembled. Surrounding the enlarged part of the take-up and abutting the enlarged end of the thimble 7, a jam-nut 11 abuts for purposes of adjustment and to prevent the loosening of 105 the parts.

Besides providing for minute adjustment thru the loosening of the jam-nut 11, and turning the take-up B after the tappet A and its jam-nut are tightened on the shank 110 3 of the take-up, the tappet and the associated adjustments may be removed from an

engine independent of the push-rod C, and vice versa.

From the foregoing explanation of the operation and advantages of my invention, a more extended résumé, is believed will not be necessary.

Having therefore set forth my invention what I claim as new and desire to secure by Letters Patent is:—

- 10 1. A tappet having a reduced interiorly screw-threaded stem, a slack take-up having a reduced exteriorly screw-threaded shank screw into said stem, a jam-nut fitted on said shank and abutting said stem, said take-up having an enlarged screw-threaded extremity, a thimble screw-threaded onto said enlarged screw-threaded extremity, a push-rod having an annular groove near its upper end fitted into a reduced open end of 15 said thimble and abutting said take-up, a split ring fitted into said annular groove and occupying a position within the bottom of 20 said thimble and its interior wall to pre-

vent the withdrawal of said push-rod, and means to prevent the loosening of said thimble when said push-rod and take-up are in abutting position.

2. A tappet head having a reduced interiorly screw-threaded stem, a slack take-up having a reduced exteriorly screw-threaded shank screwed into said stem, a jam-nut fitted on said shank and abutting said stem, said take-up having an enlarged screw-threaded extremity, a thimble screw-threaded onto said enlarged screw-threaded extremity, a push-rod having an annular groove near its upper end fitted into a reduced open end of said thimble and abutting said take-up, a split ring fitted into said annular groove and occupying a position within the bottom of said thimble and its interior wall to prevent the withdrawal of said push-rod, and a jam-nut run on the enlarged end of said take-up and abutting said thimble to prevent the loosening of the parts.

ITALO VIRONDA.
